UNITED STATES PATENT OFFICE.

GEORGE HAYES, OF NEW YORK, N. Y.

SWIMMING DEVICE.

SPECIFICATION forming part of Letters Patent No. 242,773, dated June 14, 1881.

Application filed April 13, 1881. (No model.)

To all whom it may concern:

Be it known that I, GEORGE HAYES, a resident of the city, county, and State of New York, have invented certain new and useful 5 Improvements in Swimming Devices, of which the following is a specification.

My invention relates to appliances intended to facilitate the operation of swimming; and it consists in peculiarly-formed web-paddles, 10 one set for the hands, and one set for the feet, adapted to be readily grasped or attached, and of such form as to shed water on the upper side, and hold or grasp water on the other, and thereby constitute a means whereby an 15 expert swimmer may obtain increased speed, and an inexpert swimmer be enabled to propel himself through the water with some certainty of reaching the goal to which his desires tend. They form a web-extension, enlarging the grasping-surface of both hands and 20 feet, and may be made of any suitable material which will have sufficient stiffness to secure proper bearing upon the water.

In the accompanying drawings, Figure 1 25 represents a top view of a hand-paddle; Fig. 2, a perspective of the same. Fig. 3 represents a top view of a foot-paddle; Fig. 4, a perspective of the same. Fig. 5 is a cross-section of a hand-paddle. Fig. 6 is a cross-section of a foot-paddle. Fig. 7 is a lengthwise 30 section of a foot-paddle, showing a sandal therein, (with a foot,) represented by dotted lines.

These paddles form a web surrounding partially or wholly the hand or foot, and the hand or foot when placed therein forms, when in action, a part thereof to the extent of filling up a central space designed for them to occupy.

a represents the web; *b*, the space occupied 40 by the hand or foot when in use.

The hand-paddle is provided with grasping-bar *c*, to enable the hand to obtain secure gripe, and it is also provided with a wristlet, *d*, to give bearing and leverage. A strap through 45 slots *e* serves to secure the paddle to the hand, as desired. To enable the fingers to pass around the grasping-bar, a slot is made at *f*, the metal of which, after cutting, is bent over forward, to give strength to that portion of the web,

as shown at *g*, and also to protect the fingers 50 against the raw edge of the metal.

The foot-paddle has web *a* and space *b* for the foot, similar to the hand-paddle, it being formed, essentially, on the same principle.

A toe-cap is shown at *h*, and at *i* and *j* are 55 shown bands extending under the sole of the foot or sandal to secure the same.

In Figs. 4, 6, and 7 the sandal is shown, (marked *k*;) which may or may not be combined therewith, as desired.

Straps *e* secure the paddle to the foot, about 60 as shown by the dotted lines in Fig. 7.

This invention promotes speed in swimming, either for pleasure or the saving of life, or as an auxiliary to life-saving devices in conjunction with floating or life preservers.

The foot-paddle may be made of rubber, similar to an overshoe, the whole being formed in a mold in one piece, or it may be attached to the usual canvas bathing-shoe, or it may be 70 stamped out of a single sheet of metal, and may be combined with or attached to a sole.

Swimmers using these paddles are not so liable to cramp and exhaustion as they would be in paddles wherein the foot or hand is kept 75 in a rigid, strained, or confined position, as in these improved paddles the hand and foot are not rigidly confined or strained.

The hand may be released entirely without removing the paddles, and when in use the 80 hands and feet are in a flexible condition and without restraint.

What I claim as new, and desire to secure by Letters Patent, is—

1. A hand-paddle so shaped and constructed 85 as to form a rigid web, *a*, extending outwardly from the hand on a line therewith, provided with space *b*, for reception of the hand, allowing free play therein and surrounding the hand, so as to broaden the expanse thereof, 90 essentially as and for the purpose set forth.

2. A web hand-paddle provided with grasping-bar *c* and wristlet *d*, as and for the purpose set forth.

3. A foot-paddle so shaped and constructed 95 as to form a rigid web, *a*, extending outwardly on a line with the foot, and provided with space *b*, for the reception of the foot, surrounding

the same, so as to broaden the expanse thereof, and of convex surface above and concave beneath, essentially as and for the purpose set forth.

- 5 4. A web foot-paddle provided with toe-cap *h*, sole-bands *i j*, and slots *e'*, essentially as and for the purpose set forth.
5. In combination with a web foot-paddle

constructed as herein set forth, the sandal *k*, arranged therein substantially as and for the purpose set forth.

GEORGE HAYES.
